COOKING STOVE WITH THERMO-ELECTRIC STORAGE

Filed April 15, 1926

Inventor:

Secondo Sacerdote

By *Lucie Girello*
Attorney

UNITED STATES PATENT OFFICE.

SECONDO SACERDOTE, OF MILAN, ITALY.

COOKING STOVE WITH THERMOELECTRIC STORAGE.

Application filed April 15, 1926, Serial No. 102,189; and in Germany April 18, 1925.

This invention relates to cooking stoves provided with electrically-heated accumulating or storage elements.

Cooking stoves are known in which the heat, generated without interruption for the twenty-four hours, by electric heating elements, is stored in bodies having a large heating capacity.

The efficiency of these stoves is lowered by reason of losses by radiation which make themselves felt during the whole twenty-four hours. It is in consequence necessary in these stoves carefully to protect the accumulating or storage bodies against radiation to the outside, which is difficult as regards their upper surface with which the kitchen utensils come into contact. This has been attempted by the provision of recesses in the storage bodies, the bottom walls 20 of which recesses constitute the heating surfaces in question and which are closed by insulating plugs; but while such arrangement has given good results from the thermic standpoint, it hinders the cook and makes 25 cooking difficult.

This invention has for its object to improve the efficiency of such stoves and at the same time render them more convenient. Stoves provided with these improvements 30 are characterized by the fact that various plugs or stops of reduced height are placed in the aforesaid recesses in such a manner that they can slide laterally in grooves without leaving the wall which encloses the 35 stove, thus preventing any loss of the heat contained in the plugs.

The accompanying drawing shows, by way of example, two methods of carrying out the present invention.

40 Figure 1 shows in vertical section, a stove suitable for family use.

Figure 2 shows in transverse vertical section a range suitable for hotels and other similar applications.

45 In the arrangement shown in Figure 1, the heat-accumulating or storage block 1 in which the thermo-electric elements 2 are disposed, is protected laterally by a refractory and insulated wall 3; its bottom may constitute the top of a cooking oven (not shown) and its upper surface forms the sole of the cooking chamber 4. Above this block are disposed plugs 5, 6, 7 and 8 made of copper, which can slide laterally in order 50 to cover and uncover the surface of the block if necessary.

The two blocks of each tier 5-7 and 6-8, can be replaced by simple blocks in guides but in that case the stove will assume a shape which is asymmetric and thus unsuitable. 60 For the economical types, it is possible to employ the combination of two partial blocks, disposed in two different tiers, for example 5 and 8 or 6-7. However, the multiplicity of blocks has the advantage of improving the thermal insulation by the effect of the interposed cushions of air and the effects of the reflection from the under surfaces of the blocks. 65

During the operations of cooking the 70 losses of heat may become considerable, since the block-protecting plugs are withdrawn. To eliminate these losses, covers 9, 9¹, themselves mounted in guides, may be employed which have sufficient height to surpass the 75 greatest height of the utensils employed. These covers may be made of enamelled iron if an insulating and heat-reflecting enamel be used, and they may also conveniently be provided with openings 10, 10¹ to allow the 80 escape of fumes. When these covers are in place, they form a closed cooking chamber, almost an oven; it is also possible to introduce into the interior of these covers electric heating elements, which may be inserted in 85 the circuit when the cover is closed, whereby the heating chamber becomes a true oven.

In the construction shown in Figure 2, there is illustrated a stove with two fronts more suitable for use in hotels, restaurants 90 and the like. In this case, the accumulator blocks 1, 1¹ can be covered by the plugs 5 and 8 sliding in a direction normal to the two faces of the stove, preferably so that they are superposed in the centre of the 95 stove. Covers of enamelled iron 9, 9¹ assume a more complete insulation during accumulation and during use. This arrangement allows of lengthening the stove as much as is necessary and without limitation. 100

The constructional details of the stoves may be varied without departing from the spirit of the invention.

I claim as my invention:

1. An electric cook stove, comprising a 105 casing; a cooking chamber therein; heat-storing means disposed in said chamber and provided with internal electric heating elements; and a plurality of protecting plugs disposed immediately above said storage 110 means and movable laterally independently of and relatively to each other, while re-

maining entirely within the confines of the casing walls, to cover or uncover the upper surface of the storage means.

2. An electric cook stove, comprising a casing; a cooking chamber therein; heat-storing means disposed in said chamber and provided with internal electric heating elements; a plurality of protecting plugs disposed immediately above said storage means and movable laterally independently of and relatively to each other, while remaining entirely within the confines of the casing walls to cover or uncover the upper surface of the storage means; and covers of heat-insulating

and reflecting material mounted for sliding movement immediately above and relatively to said plugs to close the space above the storage means when the plugs themselves have been moved into position to uncover said means.

3. An electric cook stove, according to claim 1, in which the several protecting plugs are arranged to slide in a plurality of superposed horizontal planes, whereby they may be brought into superposed position in the median part of the stove.

In testimony whereof I affix my signature.

SECONDO SACERDOTE.
